E. R. SUTTON.
CAR UNLOADER.

APPLICATION FILED FEB. 19, 1920. RENEWED FEB. 14, 1921.

1,390,591.

Patented Sept. 13, 1921.

Inventor.
Edward F. Sutton
by M. Van P. Hastings,
his Attorney.

UNITED STATES PATENT OFFICE.

EDWARD R. SUTTON, OF PHILADELPHIA, PENNSYLVANIA.

CAR-UNLOADER.

1,390,591.

Specification of Letters Patent. Patented Sept. 13, 1921.

Application filed February 19, 1920, Serial No. 359,975. Renewed February 14, 1921. Serial No. 445,015.

To all whom it may concern:

Be it known that I, EDWARD R. SUTTON, a citizen of the United States, residing at Philadelphia, in the county of Philadelphia and State of Pennsylvania, have invented 5 certain new and useful Improvements in Car-Unloaders, of which the following is a specification.

This invention relates to certain new and 10 useful improvements in devices for unloading cars and the like.

The principal object of the invention is the provision of individual supports of graded heights and means for connecting 15 same in spaced relation with each other to form an inclined runway or trestle of novel construction adapted to be positioned on the same rails as the car to be unloaded.

With the aforesaid, and other, objects in 20 view my invention therefore consists in the device for unloading cars, as illustrated, in the form which I now think preferable, in the accompanying drawings, and as will be hereinafter described in detail, and then 25 definitely set forth by the claim appended at the end hereof.

In the accompanying drawings which represent the preferable embodiment of my invention,

30 Fig. 1 is a side elevational view of my device assembled and in position on a railroad track preparatory to unloading a car on said track;

35 Fig. 2 is a cross sectional view on line 2—2 of Fig. 1 illustrating the construction of an individual support;

Fig. 3 is likewise a cross sectional view on line 3—3 of Fig. 1, and

40 Fig. 4 is a detail view of the means of securing the lower end of the runway to the track.

Like reference characters refer to like parts throughout the drawings.

Referring to said drawings in detail the 45 character A denotes a section of railroad or railway track secured to ties B in the conventional manner. Said track A being adapted for the passage thereover of a car C.

50 A plurality of individual supports E are provided of graded heights so that when assembled in position and in spaced relation with each other, and braced as herein-after described, they form an inclined runway or trestle D, extending from the car

C to said track A, as particularly illustrated in Fig. 1, the bases of said supports resting upon said track A.

Each individual support E is provided with the angle braces I bolted adjacent the intersections of the corners of said supports, said intersections being likewise bolted together, all as particularly illustrated in Fig. 2.

A horizontal brace G, extending substantially the length of the trestle D is bolted to the individual supports E near their respective bases and an inclined brace F is likewise bolted to said individual supports adjacent the tops thereof. In order to more 65 securely hold said supports E in position and in spaced relation with each other additional connecting braces H are provided between each of said supports and are bolted thereto as illustrated in Fig. 1. 75

When said supports E are assembled in position and braced, as just described, a plank (or planks) J is placed on the tops of said supports, forming a gangway down which the material being unloaded from the 80 car may be taken.

The end of the gangplank J is secured in a firm position to the track A in the following manner, viz:—between said gangplank J, and secured therebeneath, and the track 85 A, an angle iron support K is positioned, having an opening therein for a bolt L, said bolt L extending down alongside the outer edge of the rail A and being bolted at its opposite end to a cleat M beneath the 90 under part of said rail A. This construction is particularly illustrated in Fig. 4.

Angle iron supports N are provided between the bases of the supports E and the inside portion of the tread of the rails comprising the track A, so that by means of bolts O therethrough said supports may be held firmly in position on said track. 95

In order to accommodate the varying heights of cars the first three individual 100 supports E are illustrated as being constructed in two sections, i. e., E₁ and E₂, whereby said supports may be extended to varying heights. Multiple bolt openings P are provided through the sections E₁ and 105 E₂, so that they may be bolted together in such extended position. Like multiple bolt openings Q are provided in the connecting braces H to meet the varying extensions of said supports E.

A block R is provided between the wheel of the car C and the initial support E to hold said support more firmly in position.

The device just described may be readily assembled in position on the track adjacent to the car to be unloaded and the contents of the car can be quickly and efficiently unloaded with its use. It can then be readily disassembled and will occupy but a small space when not in use. Its use will be obvious in unloading cars containing objects of bulk and weight.

When disassembled it can be shipped in the car with the material to be unloaded and then placed in position when the car reaches its destination. Ofttimes material is shipped to points where there are no cranes or other facilities for unloading; the present device, in such instances will prove of great utility.

Minor modifications, not involving invention, may be made to the device, without

departing from the spirit or scope of my invention.

Having thus described my invention what I claim as new and desire to secure by Letters Patent is:—

The combination with a railroad track of a car unloader, comprising a plurality of individual supports of graded heights, braces connecting the individual supports in spaced relation with each other to form an inclined trestle, the bases of each of said individual supports being adapted to be positioned on the track adjacent the car to be unloaded, a gangway positioned on said trestle, means whereby the supports adjacent the car may be adjusted as to height to meet the varying heights of cars and means to secure the gangway to the track, substantially as shown and described.

In testimony whereof I affix my signature.

EDWARD R. SUTTON.
